UNITED STATES PATENT OFFICE.

JOSEPH H. COHEN, OF BRIDGEPORT, CONNECTICUT.

DESIGN FOR A CIGAR LIGHTER.

Application filed June 22, 1926. Serial No. 18,144. Term of patent 14 years.

To all whom it may concern:

Be it known that I, JOSEPH H. COHEN, a citizen of the United States, residing at Bridgeport, in the county of Fairfield and State of Connecticut, have invented a new, original, and ornamental Design for Cigar Lighter, of which the following is a specification, reference being had to the accompanying drawing, forming part thereof.

The figure is a perspective view of the cigar lighter showing my new design.

I claim:

The ornamental design for a cigar lighter, as shown.

JOSEPH H. COHEN.
